UNITED STATES PATENT OFFICE.

JOHN S. McNAMARA, OF PATERSON, NEW JERSEY, ASSIGNOR TO VAN VLAANDEREN MACHINE COMPANY, OF PATERSON, NEW JERSEY, A CORPORATION OF NEW JERSEY.

SPRAY NOZZLE.

Application filed January 12, 1927. Serial No. 160,542.

This invention relates to apparatus for treating fabrics in the rope form with liquids, as phosphating liquids and water for washing, and in particular to that type 5 of nozzles for supplying the liquid to the fabric in which the fabric extends and is drawn through a passage in the nozzle and the liquid is delivered to the fabric radially from various points around the fabric, as 10 in an endless surrounding spray or stream. In any form of nozzle of this class heretofore known or used the spray or stream delivery outlet was the outlet of a chamber surrounding the passage and to which the 15 liquid-conducting pipe directly led. In consequence, the spray or stream, instead of having a force which was desirably uniform all around, was appreciably weaker at the point diametrically opposite the connection 20 of the liquid-conducting pipe with said chamber than at the point of such connection, so that the fabric was not uniformly impregnated and was also impelled against the side of the passage, undergoing harmful 25 rubbing as it was drawn through the passage. The present invention consists in part in supplementing the mentioned, or what I term the spray, chamber with a chamber whose function it shall be to distribute the 30 liquid at as nearly as possible uniform pressure all around to the first chamber, whereby to overcome the mentioned fault. In the best form of the invention the outlet from the spray chamber is continuous or practically so, existing as a slit, and it delivers the main spray or stream to the fabric, more or less deluging the same, and the distributing chamber has all around a series of 35 needle-spray outlets which deliver numerous smaller sprays with superior force calculated 40 to break down any matting together of the fibres of the fabric and so insure a thorough wetting of the whole of the fabric mass.

In the drawing,

45 Fig. 1 is a view in plan of the improved nozzle, partly broken away; and

Fig. 2 is a central vertical sectional view of the nozzle.

The nozzle as herein shown by way of 50 example comprises two main or upper and lower parts, together forming the mentioned passage and together forming the spray chamber and the lower one forming the distributing chamber.

55 The upper part, apertured vertically, has

a flaring top or mouth portion 1, and a substantially cylindrical lower portion 2 whose diameter is somewhat greater than the least (or basal) diameter of the flaring mouth portion, being joined thereto by its annular 60 top wall 2^a; the base of the portion 2 is formed with an external flange 3.

The lower part, also apertured vertically, has a cylindrical chamber 4 extending around its aperture and from the base of 65 said part upward a distance somewhat more than one-half the height thereof, leaving an upstanding lip or flange 5 projecting upwardly from it. Near the top of the chamber 4 and opening outwardly therefrom at 70 equidistant points around the same are (in the present example) eight uniformly gaged ports or outlets 6. This lower part has an external circumferential flange 7 and said flange has in its upper side a rabbet 8. The 75 rabbet has a radial depth such that the base of the portion 2 of the upper part of the device will fit snugly over the thus-rabbeted flange in the manner shown in Fig. 2 and that when the parts are thus assembled a circumferential space will exist to 80 form the main chamber 9; the elevation of the flange and the vertical depth of the rabbet are such that when the upper part is fitted to the lower part of the device in 85 the manner shown, with a rubber or other yielding gasket 10 interposed between the flange 3 and the bottom of the rabbet and bolts 11 made to secure the parts together and to cause the gasket to seal the joint between them, a circumferential space or slit 12 will exist between the top of flange 5 and the overlying wall 2^a of cylindrical portion 2, forming the outlet from chamber 9. Preferably in more than one plane, as one 90 near the top and the other near the bottom of the chamber 4, said chamber has a circumferential and uniformly spaced series of 95 small or needle-spray outlets 13.

The liquid conducting pipe 14, delivering 100 into chamber 4, is adapted to be connected to chamber 4 as shown and forms its inlet.

When the device is in use the liquid flows from the pipe 14 into the space 4, through the ports 6 into the space 9 and then via 105 the slit 12 into the passage of the nozzle together formed by the apertures of its two parts, through which passage it will be understood the rope of fabric is caused to travel, as in the downward direction. 110

In previous devices of this class the liquid flow from the source of supply took place directly into a chamber, as 9, surrounding the fabric passage and having a circumferential outlet, such as 12 to said passage, and as already indicated the consequence of this construction was that the liquid was delivered through the slit with appreciably weaker force at the side opposite the connection with the source of supply than at the side of such supply. In my present construction the space 4 forms a liquid distributing head or chamber relatively between the source of supply and the chamber 9 having the circumferential outlet 12 and since it has means 6 permitting liquid flow from the distributing head to said chamber at various points equidistantly spaced from each other and maintaining such flow at said various points at a substantially uniform rate the delivery from chamber 9 through slit 12 is appreciably more uniform all around than heretofore.

The liquid from the slit 12 acts to deluge the goods, but I find that in order that the goods may be thoroughly wetted all through it is desirable to provide means to break up any matting together of the fibres; wherefore the supply outlets 13 are used, thus delivering the liquid in more or less violent jets which have the effect of agitating and loosening the fibres so that the wetting of the fabric by the liquid becomes complete.

In reassembling the parts after separating them, as for cleaning, it is desirable that there should be means for gaging the extent to which one is slipped over the other and hence the width of the slit 12. Hence one of the flanges 3 and 7 has set-screws 15 tapped into it in alternation with the bolts 11 and adapted to bear against the other of such flanges.

Having thus fully described my invention what I claim and desire to secure by Letters Patent is:

1. A nozzle of the class described having an upright passage therethrough through which the fabric to be treated is to pass, an annular liquid chamber extending around and having means to discharge liquid therefrom into the passage at substantially all points around the same, and a liquid distributing head also arranged around said passage and having means to discharge liquid flow from the head to said chamber at various points equidistantly spaced from each other around the passage and at said

various points at substantially uniform rate.

2. A nozzle of the class described having an upright passage therethrough through which the fabric to be treated is to pass, an annular liquid chamber extending around and having means to discharge liquid therefrom into the passage, and a liquid distributing head also arranged around said passage and having means to discharge liquid flow from the head into said chamber and also directly into the passage.

3. A nozzle of the class described having an upright passage therethrough through which the fabric to be treated is to pass and an outlet for flow of liquid to said passage and jet outlets for flow of liquid to said passage each less in size than the size of the first outlet and directed toward the path of travel of the goods and at an elevation below the first-named outlet.

4. A nozzle of the class described having an upright passage therethrough through which the fabric to be treated is to pass, annular liquid chambers extending around said passage and having restricted communication with each other, each chamber having means to discharge liquid into said passage.

5. A passaged nozzle of the class described including two apertured parts arranged one within and movable with respect to the other and so that the apertures thereof together form the passage of the nozzle, there being a liquid space around the passage and between said parts and a liquid chamber around the passage and in one of said parts, said space and chamber communicating with each other and one having means to discharge liquid into the passage.

6. A nozzle of the class described having an upright passage therethrough through which the fabric to be treated is to pass and an outlet for flow of liquid to such passage and jet outlets for flow of liquid to said passage each less in size than the size of the first outlet and directed toward the path of travel of the goods and at an elevation different from that of the first-named outlet.

7. A nozzle of the class described having an upright passage therethrough through which the fabric to be treated is to pass, annular liquid chambers extending around said passage and having restricted communication with each other and one such chamber having a liquid supply inlet and the other having means to discharge liquid into said passage.

In testimony whereof I affix my signature.
JOHN S. McNAMARA.
